UNITED STATES PATENT OFFICE

DONALD E. EMERSON, OF ST. PAUL, MINNESOTA

RADIO STATIC ELIMINATOR

Application filed June 29, 1929. Serial No. 374,654.

This invention appertains to attachments for radio receiving sets and more particularly to a novel device for use in conjunction with a radio receiving set to eliminate static and other disagreeable noises generally transmitted to the set by the antenna or aerial.

One of the primary objects of my present invention is to provide a radio receiving set static eliminator embodying a hard rubber tube or other tube made of insulating material filled with soft wax or the like and through which extends a conductor wire connected to caps carried by the opposite ends 15 of the tube, the caps carrying means for connecting the tube to a suitable panel and for receiving the lead-in wire from the antenna or aerial and the wire leading to the aerial post of the receiving set, the soft wax 20 or other like material tending to absorb and eliminate the static picked up by the aerial or antenna.

A further object of my invention is to provide a device of this character which also 25 constitutes a convenient means for attaching the ground and aerial wires to the set, the device being adapted to be secured to the window sill and has means associated therewith for permitting the ground and antenna wires to be connected therewith, whereby the hook-up wires for the ground and 30 aerial posts of the set can be readily connected with the panel.

A still further object of my invention is 35 to provide a static eliminator for radio receiving sets of the above character, which will be durable and efficient in use, one that will be simple and easy to manufacture, and one which can be placed upon the market 40 at a reasonable cost.

With these and other objects in view, the invention consists in the novel construction, arrangement and formation of parts, as will 45 be hereinafter more specifically described, claimed, and illustrated in the accompanying drawing, in which drawing:

Figure 1 is a front elevation of my improved static eliminator;

Figure 2 is a horizontal section through

the same taken on the line 2—2 of Figure 1 looking in the direction of the arrows;

Figure 3 is a transverse section through the improved device taken on the line 3—3 of Figure 1;

55

Figure 4 is a detail view of the tube and associate parts removed from the panel and the various parts in their disconnected condition.

Referring to the drawing in detail, where- 60 in similar reference characters designate corresponding parts throughout the several views, the letter A generally indicates my improved device, which comprises a panel 5, which can be formed of bakelite or other 65 non-electric-conducting material. The panel 5 may be provided with suitable openings adjacent to the opposite ends thereof for the reception of fastening screws 6 whereby the panel can be conveniently secured in place 70 at the desired point, either directly to the woodwork of the receiving set or to a window sill adjacent to the lead-in wire from the antenna and the ground wire.

Arranged longitudinally on one face of the 75 panel 5 is the novel static eliminator per se which comprises a barrel or tube 7, preferably formed of hard rubber, bakelite or the like, and the opposite ends of this tube or barrel 7 are provided with internal threads 80 for the reception of metallic end caps 8 and 9. These caps can be formed of electric conducting material and are each provided with a threaded bore 10 for the reception of the end connector plugs 11 which have formed 85 thereon binding post lugs 12. The plugs 11 are provided with relatively short internally threaded bores 13 for the reception of the threaded ends of a metal electric conductor rod 14, which as shown extends longitudinally through the barrel in spaced relation to the inner surface thereof. The lugs 12 are apertured for the reception of the threaded shanks 15 of fastening members 16 which 90 can be anchored or secured in the front face of the panel 5 in any desired way. The threaded shanks 15 of the fastening elements 16 form binding posts for the reception of the aerial lead-in wire 16' and the connector wire 17 which leads to the aerial binding post on 95 100

the radio set. The barrel or tube 7 is adapted to be filled with soft wax or similar material 18 which material functions to absorb the static or other objectionable noises picked up by the antenna and it is to be noted that the radio waves pass through the center of the wax by means of the rod 14.

The panel 5, below the barrel or tube 7, has secured thereto a binding post 20 which provides a convenient means for permitting the ground wire 21 leading from the outside of the building to be connected to the panel and the connector wire 22 leading to the ground post on the set to be connected to the panel. Thus the entire device constitutes a convenient connection panel to facilitate the connecting of the various wires to a radio receiving set.

If desired, the tube or barrel 7 and its associate parts can be made standard equipment on a radio receiving set and thus connected directly with the set either in front of or in rear of the conventional aerial binding post on the set.

Changes in details may be made without departing from the spirit or the scope of this invention, but:

What I claim as new is:

1. A static eliminator for radio receiving sets comprising a barrel formed of insulating material, heads formed of electric conducting material secured to the opposite ends of the barrel, a conductor rod extending axially through the barrel and electrically connected with said heads, soft wax in said barrel surrounding the conductor rod, and means for connecting a lead-in wire from an aerial and a connector wire leading to the binding aerial post of the radio receiving set to the opposite ends of the heads.

2. A static eliminator for radio receiving sets comprising a barrel formed of electric insulating material having soft wax therein, an electric conductor rod extending axially through the barrel and embedded in said wax, caps formed of electric conducting material threaded into the opposite ends of the barrel and having sockets therein, plugs threaded into said sockets receiving the opposite ends of the conductor wire, binding post lugs formed on said plugs, means engaging said lugs for connecting the same to a support, and forming means for permitting the connection of the lead-in wire from the antenna and the connecting wire for the radio receiving set aerial binding post to be connected therewith.

3. A static eliminator for radio receiving sets comprising a panel formed of insulating material, means for securing the panel to a support, a barrel formed of electric insulating material having a soft wax-like material therein, an electric conductor rod extending axially through the barrel and embedded in said wax-like material, end caps threaded into the opposite ends of the barrel and having

threaded bores, plugs threaded into said bores receiving the opposite ends of the conductor rod, connector apertured lugs formed on the outer ends of the plugs, means for anchoring the lugs to the panel including fastening members embedded in said panel and having threaded shanks extending through the apertures of the lugs, said shanks forming binding posts for receiving respectively the aerial lead-in wire and the connector wire extending to the aerial binding post on the radio receiving set, and a third binding post carried by the panel below the barrel for permitting the connection of the ground wire and the connecting ground wire to be connected with the panel.

In testimony whereof I affix my signature.

DONALD E. EMERSON.
